CLAIM

The ornamental design for a linear guideway, as shown and described.

DESCRIPTION

FIG. 1 is a front elevational view of a linear guideway showing my new design;

FIG. 2 is a top plan view thereof; a bottom plan view is a mirror image of the top plan view;

FIG. 3 is a left side elevational view thereof;

FIG. 4 is a right side elevational view thereof;

FIG. 5 is a front, top, left perspective view thereof; and,

FIG. 6 is a rear, bottom, left perspective view thereof.

1 Claim, 2 Drawing Sheets
